ATTORNEY

UNITED STATES PATENT OFFICE.

RAYMOND N. EHRHART, OF EDGEWOOD, PENNSYLVANIA, ASSIGNOR TO WESTINGHOUSE ELECTRIC & MANUFACTURING COMPANY, A CORPORATION OF PENNSYLVANIA.

CONDENSER.

1,364,921.

Specification of Letters Patent. Patented Jan. 11, 1921.

Application filed November 8, 1918. Serial No. 261,709.

To all whom it may concern:

Be it known that I, RAYMOND N. EHRHART, a citizen of the United States, and a resident of Edgewood, in the county of Allegheny and State of Pennsylvania, have made a new and useful Invention in Condensers, of which the following is a specification.

This invention relates to surface condensers having a cooling system including water tubes and water boxes for distributing the water through the tubes. In my United States Patent No. 1,142,784, issued June 8, 1915, I have shown a surface condenser of the radial flow type, and the present invention contemplates certain improvements in the air offtake apparatus for condensers of the type embodied in the said patent, although the invention is applicable 20 to other forms of surface condensers.

In the above mentioned patent, I have shown a circular nest or group of tubes arranged eccentrically within a cylindrical condenser shell whereby steam may enter 25 substantially the entire periphery of the nest of tubes and flow radially toward the interior of the nest. An air off-take passage, extending the entire length of the nest, is provided for withdrawing air or non-condensable fluid from the center of the nest of tubes. As shown in the patent, this passage is located between a pair of spaced plates or baffles and extends radially from the center of the nest of tubes toward the shell 30 throughout the length of the condenser. The air entering this passage is drawn off through an offtake port located at a convenient point in the shell of the condenser. 35

In large installations such an arrangement is expensive and furthermore the air off-take passage occupies space that could be occupied to good advantage by cooling tubes.

This invention has for an object to produce improved means through which the air may be extracted from surface condensers that is inexpensive, compact, and which may be readily manufactured and assembled.

Another object is to produce a means 50 through which the air may be extracted from a condenser that is highly efficient and serves as a cooling agent for the fluid withdrawn through it.

A further object is to produce a condenser having an air offtake means which may 55 serve as a diaphragm for the water box, and which is so located and arranged as to conserve space within the condenser so that the same may be utilized to the best advantage in the distribution of condensing surface. 60

These and other objects which will be made apparent by the further description are attained by means of a condenser embodying the features herein described and illustrated in the drawings accompanying 65 and forming a part of this application.

In the drawings: Figure 1 is a longitudinal, vertical section of a surface condenser, a section of the central portion being broken away to contract the figure. 70

Fig. 2 is a transverse vertical section along the line II—II of Fig. 1.

Referring to the drawings: The apparatus illustrated includes a substantially cylindrical condenser shell 1 closed at the ends 75 by tube plates 2 and 3. Mounted in, and extending between the plates, is a plurality of tubes 4 arranged in a substantially circular nest or group, which is eccentrically disposed with respect to the cylindrical shell 80 so that the center of the nest of tubes is below the center of the cylindrical shell. This arrangement of the tubes provides a crescent shaped steam space within the condenser which surrounds the tubes 4, and steam entering the condenser through the inlet 6 may therefore pass into the nest throughout substantially its entire periphery, and there is little tendency for greater amounts of steam to enter one portion of the periphery rather 85 than another. 90

As shown, the tubes 4 are arranged about a central space A from which the air is extracted by means of a conduit, to be hereinafter described. 95

The water circulating system of the condenser illustrated includes a water box 7, consisting of a cylindrical casing which is to be secured to the tube plate 2 of the condenser shell by bolts 8 or by other means. 100 This casing is provided with a diaphragm or partition 9 which separates the water box 7 into two compartments 10 and 11. The end of the water box 7 is provided with a cover 12 detachably secured to the box by bolts 13 and to the partition 9 by bolts 13'. 105

The partition 9 is also shown bolted to the tube plate 2 by bolts 14 so that water entering the compartment 11 of the box 7 through the inlet 15 cannot leak past the 5 tube plate 2 or the cover 12 into the compartment 10.

Cooling water entering the compartment 11 flows through the upper group of tubes 4 into a water box 16 formed by a convex 10 cover 17 secured to the end plate 3 by bolts 18. The water box 16 reverses the flow of the water and returns it through the lower group of tubes 4 into the compartment 10 from whence it passes through the outlet 15 19 as is the usual practice in surface condensers.

One-half of the partition 9 is hollow so as to provide a wide flat and relatively shallow air offtake passage 20 which terminates 20 at the center of the partition in an enlarged cylindrical chamber 21. This chamber communicates with the interior of the shell 1 or the condenser chamber, through a circular port 22 provided in the tube plate 2. 25 The outer end of the passage 20 terminates in a flanged connection 23, to which an ejector or air pump, not shown, may be connected.

Inasmuch as the air offtake passage 20 is 30 flat, wide and relatively shallow and is in contact with the cooling water in the compartments 10 and 11, the walls of the passage present an extensive cooling surface to the outflowing gases and any condensable 35 vapor passing therethrough is condensed by the walls of the passage before it reaches the outlet connection 23 and the non-condensable vapors are materially cooled as they traverse this passage.

40 From the foregoing it will be apparent that by so arranging the air off-take conduit that it serves as a diaphragm, the expensive off-take conduit usually required in the condenser chamber of a radial flow condenser is eliminated. It will, of course, be apparent that a tubular baffle may communicate with the port 22 and extend the entire length of the passage A without interfering with the tube distribution or occupying space which could be effectively occupied by tubes. Where such a baffle is employed it would preferably be of circular cross section and would be provided with adequate ports throughout its length.

55 As shown, the construction is such that the cover 12 may readily be removed without interfering with the air offtake passage, or the connections between that passage and the air pump. The water box 7 may also be readily 60 removed from the shell.

While I have described and illustrated but one embodiment of my invention, it will be apparent to those skilled in the art that various changes, modifications, additions 65 and omissions may be made in the appara-

tus illustrated without departing from the spirit and scope of the invention as set forth by the appended claims.

What I claim is:

1. The combination with a condenser having a divided water box, of a partition for the said water box provided with an air off-take passage establishing communication between the condensing chamber and the exterior thereof. 70

2. The combination with a condenser having a divided water box, of a partition for the said water box provided with an air off-take passage communicating with the condensing chamber at a central point and establishing communication between the condensing chamber and the exterior thereof. 80

3. The combination with a radial flow condenser having a divided water box, of a partition for the said box provided with an air off-take passage communicating with the condensing chamber. 85

4. A condenser comprising in combination a condensing chamber, a plurality of water tubes extending therethrough, a water box, and a partition dividing the water box into separate compartments, and provided with an air off-take passage communicating with the condensing chamber. 90

5. A condenser comprising in combination a condensing chamber, a plurality of water tubes extending therethrough, a water box, and a partition dividing the water box into separate compartments, and provided with an air off-take passage communicating with the condensing chamber, at a substantially central point with respect to the nest of tubes. 95

6. A condenser comprising in combination a condensing chamber, a plurality of water tubes extending therethrough, a water box, and a partition dividing the water box into separate compartments, and provided with a relatively wide and shallow air off-take passage communicating with the condensing chamber. 105

7. A condenser comprising in combination a condensing chamber, a plurality of water tubes extending therethrough, a water box, and a substantially flat partition dividing the water box into separate compartments and having its walls separated to provide a flat air off-take passage between them communicating with the condensing chamber. 115

8. A condenser comprising in combination a condensing chamber, a plurality of water tubes extending therethrough, a water box, a partition dividing the water box into separate compartments and provided with an air off-take passage communicating with the condensing chamber, and a cover for the water box detachably secured to the box and the said partition. 120

9. A condenser comprising in combination a condensing chamber, a plurality of water 130

tubes extending therethrough, a water box, a partition wall integral with the box dividing the box into separate compartments and provided with an offtake passage communicating with the condensing chamber, and means for detachably securing the box to the shell of the condensing chamber.

10. A condenser comprising in combination a condensing chamber, a plurality of water tubes extending therethrough, a water box, a partition integral with the box dividing the box into separate compartments and provided with an air offtake passage communicating with the condensing chamber, means for detachably securing the box to the shell of the condensing chamber and a cover detachably secured to the box and the partition.

11. A condenser comprising in combination a condensing chamber, water tubes extending therethrough, a water box and an air offtake conduit communicating with the condensing chamber and extending through the water box and having its walls in contact with the water within the box.

12. In combination with a radial flow condenser in which the tubes are arranged in a substantially cylindrical nest located eccentrically within the condenser shell, an air offtake port provided in one tube plate of the condenser and located centrally with relation to the nest of tubes, and a passage communicating therewith and passing through the water box of the condenser.

35 13. In combination with a radial flow condenser in which the tubes are arranged in a substantially cylindrical nest located eccentrically within the condenser shell, a port formed in the tube plate and located centrally with relation to said nest, and an air offtake passage extending through the water box of the condenser communicating with said port and terminating in a flanged connection at the periphery of the water box.

14. The combination with a condenser having a water box, of an air offtake conduit extending into the water box and establishing communication between the condensing chamber and the exterior thereof.

15. The combination with a condenser having a water box, of an air offtake conduit extending through the water box and establishing communication between the condensing chamber and the exterior thereof.

16. The combination with a condenser having a water box, of an air offtake conduit having a portion of its wall exposed to the water in the box and establishing communication between the condensing chamber and the exterior thereof.

17. In combination with a radial flow condenser provided with a water box and in which the tubes are arranged in a substantially cylindrical nest, an air offtake port provided in one tube plate of the condenser and located centrally with relation to the nest of tubes, and a conduit communicating therewith and passing through the said water box.

In testimony whereof, I have hereunto subscribed my name this 5th day of November, 1918.

RAYMOND N. EHRHART.
